A. COTTON

WATER TUBE BOILER

Filed March 15, 1920

ALFRED COTTON,
by Bakewell & Church ATTORNEYS

UNITED STATES PATENT OFFICE.

ALFRED COTTON, OF ST. LOUIS, MISSOURI, ASSIGNOR TO HEINE BOILER COMPANY, OF ST. LOUIS, MISSOURI, A CORPORATION OF MISSOURI.

WATER-TUBE BOILER.

Application filed March 15, 1920. Serial No. 365,808.

To all whom it may concern:

Be it known that I, ALFRED COTTON, a citizen of the United States, residing at St. Louis, Missouri, have invented a certain 5 new and useful Improvement in Water-Tube Boilers, of which the following is a full, clear, and exact description, such as will enable others skilled in the art to which it appertains to make and use the 10 same.

This invention relates to water tube boilers of the type in which the tubes are arranged horizontally, or substantially so, such, for example, as in the Heine boiler 15 now in general use.

The main object of the invention is to provide an efficient boiler of the general type referred to that can be operated successfully with gases of a lower temperature 20 than the gases obtained by direct firing, thus producing a boiler that can be operated by the heat obtained from the incineration of municipal refuse or from waste heat from industrial processes, such as cement kilns, 25 puddling furnaces, etc.

Another object is to provide a water tube boiler of the horizontal type which is so designed that the draft resistance and the 30 velocity of the gases are relatively high; which permits the gases to be taken off either from the top or from the bottom 35 of the boiler, and whose efficiency will not be reduced by the accumulation of dust on the heating surface or on the baffles of the boiler.

To this end I have devised a boiler provided with horizontal, or substantially horizontally-disposed water tubes, and transversely-disposed obstructions or baffles combined with said tubes in such a manner 40 that the entire tube bank constitutes a single longitudinal pass through which the gases flows in a number of zig-zag or sinuous streams, one above the other and each extending across the entire width of the bank, the general direction of flow of said streams being substantially parallel to or lengthwise 45 of the tubes.

Figure 1 is a vertical longitudinal sectional view, of a boiler constructed in accordance with my invention; and

Figure 2 is a vertical longitudinal sectional view of a superheater boiler embodying my invention.

When a boiler is operated by direct firing, 55 the gases enter the boiler at a temperature close to that of the fire and much of the heat is transmitted by radiation. It is well known that the rate of heat transferred from the gases to the water per unit of heating surface is greater as the velocity of the gases is increased. I have found that in boilers which are adapted to be operated by waste heat or low temperature gases it is preferable to have the gases flow nearly 60 parallel to the tubes of the boiler, instead of transversely of the tubes or across the tubes. When the gases flow across the tubes or at substantially right angles to the tubes, a high velocity impingement is confined to 65 the "up stream" side, the "down stream" side being exposed to eddies and "dead gas" only. Prior to my invention it was considered impracticable to try to utilize waste 70 gases in a conventional water tube boiler of the horizontal type, designed to produce a horizontal flow of the gases through the boiler, because the gases escape through an outlet located at the top of the boiler; and because the dust which is always present 75 in considerable quantities in waste gases will settle on the heating surface and on the baffles, thus cutting down the efficiency of the boiler and choking the gas passages to such an extent that the flow of the gases is materially retarded. Attempts have been 80 made to remedy this defect of conventional water tube boilers of the horizontal type by arranging the gas outlet at the bottom of 85 the boiler, by omitting baffles in the tube bank and by providing the boiler with a hopper for collecting the dust that settles out of the gases in the passage of the gases through the boiler, and while a boiler of 90 the kind just mentioned permits the gases to be taken from an outlet at the bottom of the boiler and prevents dust from accumulating on the tubes, it is not entirely 95 satisfactory, due to the relatively low velocity of the gases and to the fact that the gases follow such a path that they do not come in direct contact with much of the heating surface of the boiler. In instances 100 where it was sought to reduce the gas passage area and increase the velocity of the gases by arranging horizontally-disposed baffles in the tube bank, it was found that 105 the dust collected on the baffles and tubes in

such quantities as to materially cut down the efficiency of the boiler and retard the passage of the gases through same.

My improved boiler has none of the objectionable characteristics of boilers of the kind above described.

(1st) It is not restricted to an outlet at the top of the boiler for the escape of the gases;

(2nd) It is of such design that it has a high draft resistance and the gases will travel through the boiler with a high velocity;

(3rd) It is provided with a means for obstructing the flow of the gases which is of such a character that the dust which settles out of the gases will not accumulate on the heating surface of the boiler or on baffles arranged in the path of travel of the gases; and

(4th) It is so constructed that the gases will impinge upon or come in direct contact with substantially the entire heating surface of the boiler. Accordingly, my improved boiler can be successfully operated by waste gases or by direct firing with powdered coal.

In Figure 1 of the drawings I have illustrated one form of water tube boiler embodying my invention. Said boiler is provided with a single longitudinal gas pass having transversely-disposed obstructions, or partitions arranged in same in such a manner that the entire tube bank constitutes a single longitudinal pass through which the gases flow, longitudinally of the tubes, in a number of undulating, superimposed streams, each of which extends the entire width of the pass, thus causing the gases to follow several tortuous or sinuous paths approximately parallel to the water tubes 1. By constructing the boiler in the manner just referred to I obtain a high draft resistance and a high velocity of the gases. The baffles or obstructions can be arranged in various ways to accomplish the results above described without departing from the spirit of my invention, but in all instances the tube bank will be equipped with a number of vertically-disposed baffle elements arranged transversely of the tube bank, one behind the other, and disposed so as to co-operate with each other to virtually form a number of transverse baffles provided with solid portions and openings disposed so as to cause the gases to flow longitudinally of the boiler tubes in wave-like or undulating paths, as indicated by the arrows in Figure 1. In the form of my invention illustrated in Figure 1 the baffle elements just referred to are formed by groups of relatively shallow, vertically-disposed baffles A and B arranged transversely of the boiler tubes 1 so as to cause the gases to flow in several superimposed undulating streams

that follow several tortuous or sinuous paths, as indicated by the reference character *x* in Figure 1. Each group A comprises several baffles arranged edgewise or vertically at different levels in the tube bank and each group B comprises several baffles arranged edgewise or vertically at different levels in the tube bank, the baffles constituting each of said groups having their horizontal edges spaced apart so as to form horizontally-disposed openings that extend across the entire width of the tube bank through which the gases flow. The baffles of the various groups A and B can either be arranged in vertical alignment, one above the other, or they can be arranged in echelon, as shown in Figure 1, the baffles constituting the groups B being arranged between the baffles constituting the groups A and opposite the spaces or openings between the horizontal edges of the baffles constituting the groups A so that the gases which flow through the openings between the baffles of the groups A will divide upon encountering the baffles B and flow upwardly and downwardly over said baffles B. While I prefer to arrange the baffles A and B so that horizontally-disposed spaces or openings are formed between the baffles constituting each of said groups, this is not essential, so long as openings in the vertically-disposed, transverse baffle elements in the tube bank are so arranged or formed that the gases will flow in tortuous or sinuous paths longitudinally of the tube bank. Instead of using separate shallow members to form the baffles, a number of relatively large, vertically-disposed baffle members provided with openings could be arranged transversely of the tube bank, one behind the other, the openings in each baffle member being so disposed with relation to the solid portions of the two baffle members between which it is positioned that the gases will follow the paths or approximate paths indicated by the reference character *x* in Figure 1.

By constructing a water tube boiler of the horizontal type in the manner above described I avoid eddies and "dead gas" pockets at the "down stream" side of the tubes, as occurs when water tube boilers of the horizontal type are equipped with transversely-disposed baffles arranged so that the gases travel transversely across the tubes through a number of serial passes, for in my improved boiler the direction of the flow of the gases relative to the tubes of the boiler is from a parallel to an oblique line. In my boiler the eddies which tend to form behind the baffles are taken advantage of to insure the impingement of the gases on the whole of the heating surface of the boiler. Another desirable feature of my boiler is that the effective area of gas passage and

consequently the average velocity of the gases can be accurately regulated and controlled by adjusting the size of the baffles and the area of the spaces between or 5 through the baffles. I believe that the rate of heat transfer is directly related to the pressure drop or draft drop of the system, and it is obvious that I can attain any amount of 10 obstruction or draft resistance by suitably proportioning and arranging the baffles of my boiler.

I prefer to make the baffles of such size that they approximate the size of the openings left between the previous baffles, so that 15 the direction of flow is not brought too near to right angles. I also prefer to construct the boiler in such a manner that approximately 3,000 to 5,000 pounds of gas will flow through each square foot of gas passage area 20 per hour. In Figure 2 of the drawings I have illustrated a superheater boiler constructed in accordance with my invention, said boiler being provided with baffles A and B of the kind shown in Figure 1, and 25 also a superheater C of any preferred construction arranged in a superheater chamber through which a portion of the gases travel. Instead of arranging the superheater C so that it will be heated by only 30 a portion of the gases that pass through the boiler, the superheater could be arranged in such a manner that it will be heated by all of the gases passing through the boiler. In both forms of my invention represented by 35 Figures 1 and 2 hoppers or other suitable devices 7 are provided for collecting the dust that settles out of the gases, and while the gas outlets 5 are preferably located at the bottom of the boiler, this is not essential, as 40 the gas outlet could be located at the top of the boiler. I have not illustrated any means for inducing a circulation of the gases through the boiler, but in practice when 45 my improved boiler is used for utilizing waste gases, a fan or other suitable suction device is connected with the gas discharge outlet 5 of the boiler.

Having thus described my invention, what I claim as new and desire to secure by Letters Patent, is:

1. A water tube boiler provided with a tube bank composed of substantially horizontally-disposed water tubes, and vertically-disposed, transverse baffle elements arranged 55 transversely of the tube bank, one behind

the other, and constructed to form solid portions and openings that are disposed so as to cause the gases to split up into a plurality of streams and flow in tortuous or sinuous paths approximately parallel to the tubes 60 constituting said bank.

2. A boiler provided with a tube bank composed of substantially horizontally-disposed water tubes, a group of vertically-disposed, transverse baffle elements arranged 65 in said tube bank, one behind the other, and each constructed to form a plurality of solid portions and openings between said solid portions through which the gases flow, and a separate group of vertically-disposed 70 transverse baffle elements arranged in the tube bank between the baffle elements constituting said first group and provided with similar solid portions and openings arranged in staggered relation with those of 75 the baffle elements of said first group.

3. A water tube boiler provided with a tube bank composed of substantially horizontally-disposed water tubes, and vertically-disposed baffle elements arranged 80 transversely of the tube bank, one behind the other and each constructed to form solid portions and openings disposed in such relation to the solid portions and openings of the other baffle elements as to cause the gases 85 to split up into a plurality of streams and flow in tortuous or sinuous paths approximately parallel to the tubes constituting said bank, and means for collecting particles of dust or other matter that settle out of the 90 gases while the gases are traveling through the tube bank.

4. A boiler provided with a tube bank composed of substantially horizontally-disposed water tubes, a group of vertically-disposed baffle elements arranged transversely of the tube bank, one behind the other and each composed of a plurality of relatively shallow baffles arranged at different levels in the tube bank and having their 95 horizontal edges spaced apart so as to form openings through which the gases flow, and an independent group of vertically-disposed baffle elements arranged transversely of the tube bank between the baffle elements of 100 said first group and composed of similarly arranged shallow baffles that are disposed in staggered relation with the shallow baffles of said first group.

ALFRED COTTON.
